US00D746166S

(12) **United States Design Patent**
Li

(10) **Patent No.:** **US D746,166 S**
(45) **Date of Patent:** **** Dec. 29, 2015**

(54) **ELECTRONIC CONTROL UNIT FOR A SECURITY SYSTEM**

(71) Applicant: **Chuango Security Technology Corporation**, Fuzhou (CN)

(72) Inventor: **Chen Li**, Fuzhou (CN)

(73) Assignee: **Chuango Security Technology Corporation**, Fuzhou (CN)

(**) Term: **14 Years**

(21) Appl. No.: **29/512,792**

(22) Filed: **Dec. 23, 2014**

(51) **LOC (10) Cl.** **10-05**

(52) **U.S. Cl.**

USPC **D10/104.1**; D13/168

(57) **CLAIM**

The ornamental design for an electronic control unit for a security system, as shown and described.

DESCRIPTION

FIG. 1 is a perspective view of an electronic control unit for a security system in accordance with the design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

1 Claim, 5 Drawing Sheets

FIG. 1

FIG. 2

FIG. 3

FIG. 4

FIG. 5

FIG. 6

FIG. 7
